(57) **CLAIM**

I claim the ornamental design for a hanging flower vase, as shown and described.

DESCRIPTION

FIG. 1 is a perspective view of a hanging flower vase showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing a bottom section of the flower vase is for illustrative purposes only and forms no part of the claimed design.
